GARMENT

Daniel W. Barmon, Buffalo, N. Y.

Application September 25, 1935, Serial No. 42,100

1 Claim. (Cl. 2—74)

This invention relates to certain new and useful improvements in garments.

The primary object of this invention is to provide a ladies' garment known in the art as the wrap-around type, smocks or other form of dresses that produce a waist line effect without the use of straps, strings or ties, etc., the garment being close fitting at the waist line to present a more finished dress effect.

- 10 A further object of the invention is to provide a ladies' garment of the foregoing character wherein the elastic cords or the like are stitched to portions of the waist line of the garment with the material of the garment shirred or gathered 15 where the elastic cords are attached to permit stretching of the garment at the waist line to accommodate different sizes, the elastic cords being placed either at the back of the garment or in spaced sections at the sides of the garment 20 with the closure fasteners for the garment preferably in the form of buttons and button holes being aligned with the elastic cords for placing the same under direct tension to accomplish a more decided 25 waist line effect.
- 25 With the above and other objects in view that will become apparent as the nature of the invention is better understood, the same consists in the novel form, combination and arrangement of parts hereinafter more fully described, shown 30 in the accompanying drawing and claimed.

In the drawing:—

Figure 1 is a rear elevational view of a ladies' garment constructed in accordance with the present invention and showing the elastic cords 35 located at the waist line of the garment and in the back thereof;

Figure 2 is a horizontal sectional view taken on line 2—2 of Figure 1;

Figure 3 is a fragmentary inner face view showing 40 three parallel rows of elastic cord stitched to shirred portions of the material of the garment;

Figure 4 is a detail sectional view taken on line 4—4 of Figure 3, showing the stitching surrounding the elastic cords and fastened to the garment;

45 Figure 5 is an enlarged fragmentary inside view of the garment, showing the stitching for attaching the elastic cords to a shirred portion of the garment;

50 Figure 6 is a fragmentary front elevational view of another form of garment, wherein the elastic cords are arranged at opposite sides of the waist line of the garment with the closure fasteners for the garment in line with the elastic cords; and

Figure 7 is a horizontal sectional view taken on line 7—7 of Figure 6.

Referring more in detail to the accompanying drawing and particularly to Figures 1 to 5, the garment may be in the form of a smock, apron or dress of the wrap-around type embodying a body portion 10 and a skirt portion 11 with an intermediate waist line area 12. The garment illustrated is of the general wrap-around type with overlapping front sections 13 and 14 as shown in Figure 2 with buttons 15 carried by the underlying section 13, adapted for passage through button holes in the overlapping section 14, the buttons and button holes being located at the front of the garment and in the waist line area 12.

In order to produce a more finished dress-like appearance, with a well defined waist line, the back of the garment at the waist line area 12 is gathered or shirred as at 16 with elastic cords 17, preferably three in number, spaced from each other and parallel are secured to the shirred portion 16 at the waist line area 12 by cover stitching 18 that overlies the elastic cords 17 and passes through the material in the garment at 18a as shown in Figure 4. The button fasteners 15 for the overlapping portions 13 and 14 of the garment are in line with the gathered and tensioned section at the back of the garment to produce a direct pull on the elastic cords when the closure means is fastened, and this direct line of pull on the elastic cord causes a more snug engagement of the waist line area 12 of the garment with the body of the wearer to produce a more decided waist line effect and in simulation of more expensive articles of apparel as contrasted with the ordinary loose fitting smocks and wrap-around garments.

In the form of invention illustrated in Figures 6 and 7, the elastic cords for producing the waist line effect are located at each side of the waist line of the garment as at 12a, the sides of the waist line of the garment being shirred with the elastic cords attached thereto in a manner similar to the form of invention illustrated in Figs. 1 to 5. The button fasteners 15a are associated with the front overlapping sections of the garment as shown in Fig. 6 and in line with the elastic portions 12a. In this form of the invention, the rear portion of the garment at the waist line presents a smooth and even appearance, while the gathered portions of the garment at the waist line overlie the hips of the wearer.

From the above detailed description of the invention, it is believed that the construction and use thereof will at once be apparent, and

while there are herein shown and described the preferred embodiments of the invention, it is nevertheless to be understood that minor changes may be made therein without departing from the spirit and scope of the invention as claimed.

5 I claim:—

In a dress of the character described having waist and skirt portions, overlapping panels at the front of the dress substantially extending from side to side, means at the waist line for holding the said panels in overlapped position, a

plurality of circumferentially extending vertically spaced elastic cords secured to the waist line of the dress by cover stitching and holding the stitched portion of the waist line in a gathered condition, said gathered portion and the means for holding the front panels in overlapped relation being circumferentially aligned and said gathered portion being spaced from the overlapping front panels.
